UNITED STATES PATENT OFFICE.

WILLIAM P. CROCKETT, OF CHICAGO, ILLINOIS.

ELECTRIC-LIGHT FIXTURE.

Application filed November 27, 1925. Serial No. 71,603.

The invention relates to an electric light fixture, and particularly that type of fixture wherein a shade is used which may be rotated to cause light from the electric lamp to be reflected in any direction which may be desired.

The electric light fixture is particularly adapted for use in any instance where it is desired to shade the lamp and cause the rays of light to be reflected in a certain direction while being enabled to rotate the shade to cause the light rays to be reflected in any other direction.

The principal object of the invention is to provide a construction which is especially useful in hospitals when a subdued light is desired, and not a full flood of light from the lamp. In order to make the light inconspicuous and not disturb the patient, or others, if the fixture is in the room, or disturb any one if the fixture is in the corridor, it is preferably placed about eighteen inches from the floor with the shade in position to cause the light rays to be reflected downwardly. In case any one should desire to use the light available from the shaded lamp, as for instance, to examine instructions, a thermometer, etc., the shade may be rotated a half turn and the light will then be reflected upwardly, or it may be rotated any amount to cause the rays of light to be reflected where desired.

The invention will be explained and more clearly understood when read in conjunction with the accompanying drawings which illustrate embodiments of which the invention is susceptible, it being obvious that changes and modifications in various details of the device may be made without departing from the spirit of the invention as expressed in the appended claims forming a part hereof.

In the drawings:

Figure 1 is a front elevation of the preferred form of electric light fixture with its supporting wall plate.

Figure 2 is a horizontal sectional view of the fixture on line 2-2 of Figure 1, but showing the shade, lamp and lamp socket in elevation.

Figure 3 is a vertical sectional view of the fixture on line 3-3 of Figure 1, but showing the lamp and the lamp socket in elevation.

Figure 4 is a front elevation of a modified form of electric light fixture.

Figure 5 is a vertical sectional view of the modified form of the fixture on line 5-5 of Figure 4.

Figure 6 is a front elevation of another modified form of the electric light fixture, and,

Figure 7 is a vertical sectional view of the second modified form of fixture on the line 7-7 of Figure 6.

The structure of the invention as shown in Figures 1, 2 and 3, comprises the relatively stationary supporting wall face plate 10, the electric lamp and lamp socket receptacle 11, and the rotatable annular apertured inner plate 12, to which is secured the lamp shade or cowl 13.

The supporting wall plate 10 may be square, as shown in Figure 1, may be circular, conforming to the outline of the inner plate and shade, or, it may be rectangular, and may embody various features, such as switches, sockets, connecting mechanism, and the like. The lamp socket receptacle 11 is formed to receive the supporting wall plate 10, the electric lamp socket 14, the lamp socket collar 15, and the electric lamp or bulb 16. The socket, collar, and lamp may be of any construction adapted to be used with the fixture, and will not be further described. Conductors 17 and 18 for supplying current to the lamp, are shown extending from the lamp socket 14.

The shade 13, which is preferably opaque, is permanently and securely fastened to the rotatable, annular apertured inner plate 12. The shade is preferably riveted to the inner plate, since the shade 13 and the plate 12 always rotate together. The shade 13 is shown with its lower portion 19 extending beyond the longitudinal central line of the lamp 16 to thereby furnish more shade than would be the case if the lower edge of the shade 13 was in line with the longitudinal central line of the lamp 16. Although the shade 13 has been shown with the portion 19 extending beyond and below the horizontal central line of the lamp, it will be understood that the shade 13 may be formed without the extended portion 19, but with the lower edge in line with the longitudinal central line of the lamp or bulb 16. In some

instances it may be advantageous, from a manufacturing standpoint, to form an annular piece of metal into a cupped or dished-in portion and a suitable peripheral flange, and then cut or saw the metal through its center and thereby produce two shades from the single piece of metal. In this form of shade it is obvious that there will not be an extended portion, such as the extended portion 19, referred to. The rivets 20 extend through the flange 21 of the shade 13, and the outer portion of half of the apertured rotating inner plate 12.

The lamp socket receptacle 11 is formed as shown, and is provided with the annular extension or guiding lip 22, which is formed to provide an annular shoulder 23. The annular lamp socket receptacle 11, with the annular extension or guiding lip 22, and the shoulder 23, are permanently and fixedly secured to the face plate 10 by means of the bolts and nuts 24 and 25. As will be seen by reference to the drawings, an annular groove 26 is formed by the assembly of the annular lamp socket receptacle 11 with the extension or guiding lip 22, the shoulder 23, and the supporting plate 10. The apertured plate 12, to which the shade is secured, rotates in the groove 26. Between the apertured plate 12 and the supporting or wall face plate 10 is interposed an annular apertured shim 27. The shim 27 may be secured to the plate 10 in any desired manner, as by the flat headed rivets 28. One or more of these shims 27 may be interposed between the two plates 10 and 12, so that a proper fit may be obtained to enable the shade 13 to be rotated in its groove in a desirable manner. It is essential that there shall be a friction fit between the movable and the relatively stationary members, so that the shade 13 may remain in the position in which it is placed upon rotation until it is desired to move it to some other position. It will be understood that it is the primary purpose of the invention to have the parts constructed in such a manner that the shade 13 may be rotated and placed in any position, and that it will remain in that position until it is moved therefrom, as, for instance, by grasping the shade 13 and rotating it to a changed position. It will thus be seen that the shade 13 may be rotated at will to cause the rays of light from the lamp 16 to be reflected downwardly or upwardly, or to either side.

In connection with the finish of the supporting wall plate 10 there is difficulty in rotating the shade 13 and the plate 12 if the wall plate 10 is finished with enamel, and it would be difficult, from a commercial standpoint, to enamel the plate 10 to the exact outer peripheral line of the plate 12. The whole of the outer surface of the plate 10 may be enameled, and the shim 27 can

then be placed on the enameled plate 10, thus affording a proper surface against which the plate 12 may contact and rotate.

In assembling the fixture the shade 13 is secured to the rotating apertured plate 12, as hereinbefore described. The lamp and socket receptacle 11 and the rotating apertured plate 12 are then placed in position, as shown. The apertured face plate 10 is then brought into place against the receptacle 11, and is secured thereto by the bolts and nuts 24 and 25, or in any other suitable manner. The lamp socket, with its collar and the lamp or bulb, may be screwed into position in the aperture of the lamp and socket receptacle 11.

The light fixture as a single unit may now be mounted in any suitable location on the wall, or as shown in the drawings, it may be mounted in a suitable receptacle or terminal box 29, which has been set in the wall. The light fixture is fastened and secured to the terminal box 29 by means of screws 30 and 31, which are countersunk in the plate 10, and extend through the inwardly extending walls or sides of the terminal box 29. As shown, the shim 27 has been perforated for the admission of the screws 30 and 31, and the apertured stationary plate 10 has also been provided with holes for the admission of the screws 30 and 31. In order to place the screw 30 in position, the shade 13, with the rotatable plate 12 fastened thereto, must be rotated a half turn until the screw hole 32 in the apertured rotatable plate 12 registers with the screw hole in the upper part of the supporting wall plate 10 for the admission of the screw 30. The screw 30 may then be put into place, and when this has been accomplished, the shade 13, and the apertured plate 12 may be rotated a half turn until the screw hole 32 registers with the screw hole in the bottom part of the supporting wall plate 10 for the admission of the screw 31. The fixture is now ready for use, and the shade may be rotated in the manner set forth.

The modified form of electric light fixture shown in Figures 4 and 5 comprises the relatively stationary combined supporting wall face plate and electric lamp and lamp socket receptacle 33, the lamp shade or cowl 34, with its flange 35, and the annular retaining ring 36. The plate and lamp socket receptacle 33 is formed to receive the electric lamp socket 37, the lamp socket collar 38, and the electric lamp or bulb 39, which latter are of usual construction. The annular retaining ring 36 is permanently and securely fastened by means of rivets, or in any other suitable manner, to the combined face plate and lamp receptacle 33. The electric light fixture may be mounted in a suitable receptacle or terminal box 40,

set in the wall. The fixture is secured in the terminal box 40 by means of screws 41 and 42, which are countersunk in the combined face plate and socket receptacle 33, and extend through the inwardly projecting walls or sides of the terminal box 40. The shade 34 of Figure 4 is shown with its lower portion 43 extending beyond the longitudinal central line of the lamp 39 to thereby furnish more shade, as described in connection with the shade of Figures 1, 2 and 3. As will be clearly seen from an inspection of Figures 4 and 5, the lamp shade may be rotated to any position desired. The shade 10 is held between the face plate and socket receptacle 33 and the retaining ring 36 by having the shade flange 35 held in the groove formed by the ring and plate. It will be noted that the retaining ring is formed in such a manner as to provide a slot or groove within which the flange of the shade may travel. It is essential that there shall be a friction fit between the movable and the relatively stationary members so that the shade 20 34 may remain in the position in which it is placed upon rotation until it is desired to move it to some other position, as described in connection with the operation of the fixture shown in Figures 1, 2 and 3.

In order to secure the fixture in the terminal box 40, substantially the same procedure must be followed with reference to the screws 41 and 42, as was done with the screws 30 and 31 of the structure of Figures 1, 2 and 3. In order to place the screw 41 in position the shade 34, with its integral flange 35, must be rotated sufficiently to expose the screw hole in the upper inwardly extending lip of the terminal box 40. The screw 41 may then be placed in position, and when this has been accomplished, the shade 34 may be returned to its normal position, whereupon the screw 40 42 may be placed in position in the lower inwardly extending lip of the terminal box 40. It is necessary, of course, that the screw holes for the admission of the screw 41 in the combined face plate and socket receptacle 33, and the upper lip of the terminal box, be below the lower line of the retaining ring 36.

A further modification of the electric light fixture is shown in Figures 6 and 7. The structure as shown in these figures comprises the relatively stationary supporting wall face plate 44, the electric lamp and lamp socket receptacle 45, and the rotatable annular apertured inner plate 53, to which is secured the lamp shade or cowl 47. The supporting wall face plate 44 is bent inwardly a sufficient distance to enable the lamp socket receptacle 45 to be suitably secured to it. The receptacle 45, which is cup-shaped, and adapted to fit within

the inwardly extending portion of the face plate, has ears or lugs 48 and 49, punched therefrom. The supporting wall face plate 44 and the lamp socket receptacle 45 are both apertured to receive the electric lamp 70 75 socket 50, the lamp socket collar 51, and the electric lamp or bulb 52.

The shade 47 is permanently and securely fastened to the rotatable annular apertured inner plate 53. The shade is preferably riveted to the plate 53, the rivets extending through the flange 54 of the shade and the plate. It will thus be seen with this type of construction that the shade and the plate always rotate together.

The lamp socket receptacle 45 has an outwardly extending annular flange 55. A plurality of bolts and nuts 56, 57, 58 and 59 are disposed in the annular flange 55. The flange 55, and the plurality of bolts and nuts provide a means which is the equivalent of a groove for supporting the rotatable annular apertured plate 53 and permitting the plate 53 and the shade 47 to rotate about the electric lamp.

The plurality of bolts serve a purpose similar to the shoulder 23, shown in Figures 2 and 3.

In assembling this form of fixture the shade 47 is secured to the rotatable apertured plate 53. The lamp socket receptacle 45 is then passed into the aperture of the plate 53 with the annular flange 55 against the inner portion of the plate 53. The bolts and nuts 56, 57, 58 and 59 are then placed in position. The wall plate 44 is next attached to the ears 48 and 49 of the lamp socket receptacle 45 by means of the plurality of screws 60 and 61. The lamp socket, collar and lamp may be screwed into position in the apertures of the lamp socket receptacle and the face plate. As thus assembled the fixture may be mounted in the terminal box 62 set in the wall. The fixture is fastened to the terminal box 62 by means of screws 63 and 64 countersunk in the plate 44, and extend through the inwardly extending walls of the terminal box 62. In order to place the screw 63 in position the shade 47, together with the apertured plate 53, is rotated a half turn until the screw hole 65 in the plate 53 registers with the screw hole in the upper part of the supporting wall plate 44 for the admission of the screw 63. After the screw 63 has been put in place the shade and attached plate may be rotated a half turn until the screw hole 65 registers with the screw hole in the bottom part of the supporting wall plate 44 for the admission of the screw 64. The fixture is now assembled ready for use and the shade may be rotated as desired.

In Figures 4, 5, 6 and 7 no shims are shown, but it will be understood that shims of suitable form and dimension may be

employed between the rotatable and stationary members.

Having thus described the invention, what I claim and desire to secure by Letters Patent, is:

1. In an electric light fixture the combination of a receptacle formed with an aperture to receive an electric light socket and lamp therefor, and also formed with an extension 10 having a guiding flange and shoulder, an apertured supporting wall face plate secured to said extension, said guiding flange, shoulder, and face plate forming a groove, an annular apertured plate rotatable in said 15 groove upon said shoulder, and a shade secured to and carried by said annular apertured rotatable plate.

2. In an electric light fixture the combination of an apertured receptacle for holding 20 an electric lamp and socket therefor, said receptacle being annular and formed with an outwardly extended flange terminating at the perimeter of the receptacle in a guiding lip, an annular shoulder formed in said 25 flange at said lip, an apertured supporting wall face plate secured to said extended flange, said extended flange, guiding lip, annular shoulder, and face plate forming an annular groove, an opaque shade covering more than one half of said electric 30 lamp, said shade having an annular apertured flange rotatable in said annular groove, and an apertured shim between said apertured face plate and the apertured flange 35 of the shade, said shade flange, shim and

face plate having frictional contact whereby said shade may be rotated to any position desired.

3. In an electric light fixture the combination of a receptacle formed with an aperture to receive an electric light socket and lamp therefor, and also formed with an extension having a guiding flange and shoulder, a supporting wall face plate secured to said extension, said supporting wall face 40 plate having a central aperture within which said receptacle is fitted and two relatively small apertures oppositely disposed on either side of said central aperture for the admission of means to secure said fixture to the wall or a conduit box, said guiding flange, shoulder and face plate forming an annular groove, a substantially semi-circular shade having an annular flange, the flanged shade 45 fitting into said groove and being rotatable therein, said flange of said shade having one aperture below said shade adapted to register with one of said relatively small apertures in said face plate when said shade is at the top of said face plate, and said flange 50 covering the other relatively small aperture in said face plate, the aperture in the shade flange being adapted to be brought into registry with the upper aperture in the face plate when securing the fixture to the wall 55 or a conduit box.

In witness whereof, I hereunto subscribe my name this 24th day of November A. D., 1925.

WILLIAM P. CROCKETT.
